Aaron Vatow.

United States Patent Office.

AARON VOTAW, OF NEW GARDEN, OHIO.

Letters Patent No. 65,620, dated June 11, 1867.

CHURNS.

The Schedule referred to in these Letters Patent and making part of the same.

TO ALL WHOM IT MAY CONCERN:

Be it known that I, AARON VOTAW, of New Garden, in the county of Columbiana, and State of Ohio, have invented certain new and useful improvements in Churns, &c.; and I do hereby declare that the following is a full and complete description of the construction and operation of the same, reference being had to the accompanying drawings, making a part of this specification, in which—

Figure 1 is a side view.

Figure 2 is a horizontal section in the direction of the line $x-x$ in fig. 1.

Like letters of reference refer to like parts in the views.

A represents the foot-piece. From this extend up the standards or posts B. D D' are braces secured to the base of foot-piece A and standards B, which are to aid in strengthening and supporting said posts. The case C of the churn is balanced on the shafts a, which have their bearings in the top of the standards as shown, being secured to the sides of the case. Inside of the case, and secured to the ends of the same, are the breakers E, five at each end. There may be more or less as thought desirable. Extending across the bottom of the case are the ribs H, and two similar ones, I, secured to the top. J is the lid or cover, which is held in place when the churn is in operation by means of the rod d, which extends across the top, the ends being held in the loops e at the sides.

The churn is operated by being made to rotate, either by hand or any desirable means. The case being revolved in this way causes the cream to be thrown violently from one end of the churn to the other, the breakers at the end dividing and breaking the cream, which is further agitated by the ribs H and I as it flows over them. By this means the cream is readily and easily churned.

What I claim as my improvement, and desire to secure by Letters Patent, is—

The special arrangement of the breakers E and ribs H I, in combination with the case C, when operated in the manner and for the purpose substantially as set forth.

AARON VOTAW.
